CLAIM

The ornamental design for knife holder for electric kitchen appliances, as shown and described.

DESCRIPTION

1. Knife holder for electric kitchen appliances

1.1 : Perspective

1.2 : Perspective

1.3 : Left

1.4 : Front

1.5 : Right

1.6 : Back

1.7 : Bottom

1.8 : Top

(Continued)

The broken lines shown in 1.8 depict portions of the knife holder for electric kitchen appliances that form no part of the claimed design.

1 Claim, 8 Drawing Sheets
